UNITED STATES PATENT OFFICE.

JOHN W. HENDERSON, OF MUSKEGON HEIGHTS, MICHIGAN.

MOP-WRINGER.

1,177,623.

Specification of Letters Patent.

Patented Apr. 4, 1916.

Application filed July 2, 1913. Serial No. 776,987.

To all whom it may concern:

Be it known that I, JOHN W. HENDERSON, a citizen of the United States, and a resident of Muskegon Heights, in the county of Muskegon and State of Michigan, have invented a certain new and useful Mop-Wringer, of which the following, taken in connection with the accompanying drawings, is a specification, disclosing a preferred and practically operative embodiment of the invention, whereby others may fully understand the construction and operation of the same.

This invention relates to mop wringers of the type that are placed on the top of a pail of water which pail is adapted to receive the water wrung from the mop. In wringers of this type, it is desirable that they shall be readily and easily carried and quickly placed on and taken away from the pail, and at the same time that they shall not be liable to accidentally slip off or otherwise disengage from the pail when in operation.

It is, accordingly, a primary object of my invention to provide a wringer which may be used with a pail or other receiving receptacle, which may be put on or taken away from the pail at will and which will not disengage from the pail when in use, this being accomplished from the inherent construction of the wringer without requiring any mechanical devices of any character for fastening the wringer to the receiving receptacle. Furthermore it is desirable that the wringer shall be manually operable to regulate the wringing pressure of the operative parts of the device, and to disengage such parts when placing the mop in position to be wrung free of extra water, and my invention provides various manually operable devices for accomplishing such desired results. And these desired and improved constructions are made possible in a structure very simple in construction and operation, efficient and durable, and one of low cost of manufacture. These various desirable features and functions, together with others not specifically enumerated will be apparent as the description progresses of the device illustrated in the drawing as embodying my invention in which,

Figure 1 is a sectional view through the wringer and the pail or receptacle with which it is associated during its operation, and illustrating the wringing of a mop.

Fig. 2 is a perspective view of my improved mop wringer.

Similar reference numerals refer to similar parts throughout the views shown by the drawing.

In the embodiment of my invention shown, there is provided a frame consisting of two side members 1 having angularly bent ends 2 which ends are positioned toward each other and connected by front and rear cross pieces 3 and 4. The side members 1 are of special construction each comprising at the ends thereof horizontal sections 5 which are connected by the depressed sections 6, such depressed sections comprising a vertical portion 7 extending from the front section 5 and an inclined portion 8 extending between the lower end of portion 7 and the front end of rear section 5. The portions 5, 7 and 8 are integral and at the junction of rear section 5 and part 8 a shoulder 9 is formed as shown, the purpose of which will later appear. A roller 10 is mounted between the side members 1 of the frame, the axis of the roller passing through the point of juncture of vertical parts 7 and the inclined parts 8 of the side members.

Pivoted between the sides 1 of the frame is a second frame comprising the side bars 11 which are pivoted at 12 near the rear ends of the sides 1, roller 13 rotatably mounted between the front ends of the bars 11, and a cross member or platform 14 placed above the bars 11 and connected thereto immediately to the rear of the roller 13. The method of connection of this platform to the bars 11 may be varied but I have shown metallic members 15 having horizontal portions 16 adjacent to the undersides of the platform near the ends thereof and secured thereto by suitable fastening means 17, the vertical portions 18 passing alongside the bars 11 and terminating in seats 19 formed by turning the vertical portions back upon themselves for a short distance as shown in Fig. 2, the lower edges of the bars 11 seating in said seats. A knob 20 is attached to the upper side of the platform and a lever 21 to the under side thereof at the rear, said lever extending backward over the rear cross piece 4 as shown.

The operation of my device will be readily apparent from the above description. In the operation of wringing the mop, the

wringer is placed on the top of a pail or other receiving receptacle, shown herein at 22, and the depressed portions 6 of the side members will be located within and below the top of the pail, the horizontal portions 5 resting on the top edges of the pail. The depressed portions 6 and the roller 10 will be positioned wholly below the top edges of the pail, and any sliding movement of the wringer either to the rear or in a forward direction will be stopped by shoulders 9 and the vertical parts 7 as will be clearly evident by reference to Fig. 1. The roller 13 may be elevated either by grasping the knob 20 with the hand or by pressing on the end of lever 21 which extending from the platform acts as a lever to raise it, with its attached bars 11 and roller 13, and the mop may be placed between the rollers upon which the upper roller may then be lowered until it rests against the mop. The size or thickness of the mop is not material as the rollers may be spaced a greater or less distance apart owing to the pivotal mounting of the upper roller. After the mop has been placed between the rollers, it is drawn therebetween and pressure may be exerted to cause the upper roller to bear against the mop by placing the foot on the platform, this pressure being made as great as desired. The mop being drawn between the rollers will have the water wrung therefrom, it going into the receptacle, and as the roller 10 and the lower part of the roller 13 are positioned below the upper edges of the receptacle, any water wrung from the mop will go into the receptacle without danger of escapement from the pail or receptacle, and at the same time, the device is insured against disengagement from the pail without any fastening means being employed to secure the device thereto. After the mop has been wrung, the wringer may be taken from the pail and placed out of the way until again needed. The lever 21 may be perforated as at 23 and the wringer hung on a suitable support when not in use.

It will be noted that I have provided the parts 8 of the side members of the frame with projecting guard members 24 adjacent the ends of the roller 10 and formed to lie in close proximity to the roller. The guards project from the inner sides of the parts 8 for a short distance and are of utility in preventing the mop or any portion thereof getting between the ends of the roller 10 and the side pieces in which it is mounted which would cause the clogging of the device when attempted to be operated as will readily be perceived. The provision of these guard members one at either end of the roller forms a simple and effective guard serving to effectually prevent such undesired action.

From the foregoing it will be clear that I have provided a simple and inexpensive de-

vice which will fully perform the operations and functions desired. It consists of few parts none of which are expensive to make and is so proportioned that it may be easily and readily manipulated. The movable roller is operable toward and away from the fixed roller either by the hand as by engagement with knob 20, or it may be elevated by the foot pressing against lever 21. There are no parts to get out of order, nor any mechanism that is not capable of long and sustained use, thereby making the device one of exceptional efficiency and durability.

I have fully described a complete and operative embodiment of my invention and one found very practical and efficient in actual practice.

Various changes in minor details may be resorted to, however, without departing from the invention and I accordingly do not wish to be limited to the exact specific structure disclosed.

All modifications coming within the scope of the appended claims are included in my invention.

What I claim as new and desire to secure by Letters Patent is:—

1. In a device of the character described, a relatively stationary frame comprised of side and end bars, said end bars and portions of the side bars adjacent thereof lying in the same plane, vertical sections provided in the side bars and formed as continuations of the horizontal sections thereof at one end of the bars, inclined sections extending from the other horizontal sections of said side bars and leading to the lower ends of the vertical sections, a roller mounted between the lower ends of the vertical sections, bars pivotally mounted to the side bars on the inner sides thereof and extending normally in the same plane with the end bars to adjacent the said roller, a roller mounted between the ends of said bars and adapted to engage against the first roller, a platform mounted on said pivotally mounted bars adjacent said roller, and a lever secured to the under side of the platform and extending over one of the end bars.

2. In a device of the character described, a relatively stationary frame comprised of side and end bars, the end bars and sections of the side bars at each end thereof and adjacent the end bars lying in the same horizontal plane, vertical sections formed in said side bars as continuations of the horizontal sections of the side bars at one end thereof, inclined sections connecting the lower ends of the vertical sections and the other horizontal sections of the said side bars, a shoulder formed at the junction of each inclined section with its horizontal section, a roller mounted between the lower ends of the vertical sections, bars pivotally

mounted on the inner sides of the side bars near one end thereof, a roller mounted between the ends of said bars and adapted to engage against the first mentioned roller, 5 and means for manually operating said second roller and pivotally mounted bars toward or away from the first roller.

3. In a device of the character described, a relatively stationary frame comprised of 10 side and end members, depressed portions formed at intermediate points on said side members, a roller mounted at the lowest portions of said depressed portions, bars pivotally mounted on the inner sides of the said 15 side members and normally lying in the same plane with the uppermost portions of

the side members, a roller mounted between the ends of the bars and adapted to engage against the first roller, a platform secured to and between the said bars adjacent the 20 roller and separate foot and hand operated devices secured to said platform for manually operating the said second roller and pivotally mounted bars away from the first roller. 25

In testimony whereof, I have hereunto affixed my signature in the presence of two witnesses.

JOHN W. HENDERSON.
